UNITED STATES PATENT OFFICE.

JOHN ALLEN HEANY, OF YORK, PENNSYLVANIA, ASSIGNOR TO THE
TERER-HEANY DEVELOPING COMPANY, OF CHARLESTON, WEST
VIRGINIA, AND YORK, PENNSYLVANIA, A CORPORATION OF WEST
VIRGINIA.

MACHINE FOR FEEDING AND APPLYING FLOCCULENT MATERIALS TO WIRE.

No. 825,124.

Specification of Letters Patent.

Patented July 3, 1906.

Application filed January 20, 1904. Renewed December 22, 1905. Serial No. 292,969.

To all whom it may concern:

Be it known that I, JOHN ALLEN HEANY, a citizen of the United States, residing at York, in the county of York and State of Pennsylvania, have invented certain new and useful Improvements in Machines for Feeding and Applying Flocculent Materials to Wire, of which the following is a specification.

My invention has relation to a machine for feeding and applying a flocculent material, such as asbestos, to a rotating and traveling wire, so that said wire may be covered by a relatively compact layer of the material; and in such connection it relates to the construction and arrangement of such a machine.

In United States Letters Patent No. 740,131, granted to me under date of September 29, A. D. 1903, there is described and claimed a method of producing insulated electric conductors. Among the steps enumerated in this method is that in which flocculent asbestos is fed and applied to a rotating and traveling wire previously coated with a gluey substance. In this present application for a patent a mechanism for so feeding and applying the flocculent material forms the subject-matter of invention.

The nature and scope of my invention will be more fully understood from the following description, taken in connection with the accompanying drawings, forming part hereof, in which—

Figure 1 is a side elevational view of a machine embodying main features of my invention. Fig. 2 is a top or plan view of the same. Figs. 3 and 4 together illustrate in enlarged longitudinal section the machine of Fig. 1. Fig. 5 is a top or plan view of a portion of Fig. 4. Figs. 6 and 7 are detail views, still further enlarged, of the hopper and auxiliary mechanism for feeding the flocculent material to the carding mechanism of the machine. Fig. 8 is a top or plan view of the mechanism for feeding and rotating the wire in operative relationship with the machine for feeding and applying the material to said wire, said machine being also illustrated in plan; and Fig. 9 is a front elevational view of one end of the mechanism for feeding and rotating the wire. Referring to the drawings, *a* represents the framework of the machine, forming the support at one end for a hopper and distrib-

uting mechanism for the flocculent material at the other end for the endless card-clothing band *b* for conveying the flocculent material in proper condition to the wire *B* and intermediate of the ends for the carding mechanism *d*.

The carding mechanism may be of any desired form; but preferably it consists of the carding-drum *d'*, about the periphery of which the carding-rolls *d²*, *d³*, *d⁴*, and *d⁵* rotate. The drum *d'* delivers the flocculent material properly carded to the card-clothing band *b*, which is arranged to carry the material on the under side or plane and deliver it to the wire *B*. The wire *B* traverses the band *b* obliquely, and mechanism illustrated and described in an application filed by me under date of January 20, 1904, and serially numbered 189,804, causes the wire *B* to rotate and to travel while rotating across the band *b*. As a consequence the carded flocculent material *B'* on the band *b* is wound tightly and spirally upon the wire *B*, as illustrated in Fig. 5. The preferred mechanism for causing the wire *B* to rotate and to travel while rotating is described and illustrated in detail in said application for a patent, Serial No. 189,804, filed January 20, 1904. It is illustrated with sufficient clearness in Figs. 8 and 9 in the present application so that the function and object of the means for feeding and applying the flocculent material to the wire *B* can be readily understood. Refer-

ring to said Figs. 8 and 9, the mechanism for rotating and feeding the wire *B* consists, essentially, of a frame *A*, supporting at one end the bearings *A'*, traversed by a stationary arbor. (Not shown.) Upon this arbor is detachably secured the reel or spool *E*, from which the wire *B* is unwound. Upon a sleeve surrounding the arbor is keyed or otherwise secured a frame *F*, and the sleeve and frame *F* are arranged to be rotated upon said arbor by the pulley *A⁴*, driven from the power-shaft of the machine. The frame *F* has two arms *F²* and *F³*, on one of which is a roller *F'*, over which the wire *B* travels as it leaves the reel *E*. Each arm *F²* and *F³* of the frame *F* enters at its free end a tubular piece *G'*, through which the wire is to pass, and each arm is provided with a gear-wheel *G²*, *G³*. Each of these gear-wheels carries a grooved roller *G⁴*,

between contiguous peripheries of which rollers G^4 the wire B is clamped, rotated, and fed forward as the frame F revolves. The gear-wheels G^2 G^3 mesh with a fixed spiral 5 cam-rib G^6 , so that when the frame F is rotated these gear-wheels G^2 G^3 travel on the cam-rib G^6 and are turned in one direction to revolve the rollers G^4 , and thereby to advance the wire B . The wire B before reaching the 10 band b passes through a glue-vat D and is properly coated with an adhesive substance, such as glue, so that the material B' readily adheres to the wire B .

Referring now to the hopper and distributing mechanism for the flocculent material, the preferred construction of hopper is illustrated in detail in Figs. 3, 6, and 7. As shown, the main body of the hopper has downwardly-inclined side walls e , separated 15 at the bottom by a relatively narrow passage-way in which an endless conveyer f is arranged to travel obliquely and downwardly. The discharge end of the hopper is provided with straight wings e' , between which a block 20 g is arranged to reciprocate. For this purpose the wings e' are slotted or recessed, as at e^2 , and also provided with rails e^3 , upon which a plate g' , secured to the block g , slides, the block g itself having offsets g^2 , sliding in the 25 slots or recesses e^2 in the wings e' . The outlet from the hopper to the space between the wings e' is normally closed by the block g and by a frame g^4 , adjustable vertically in said block and carrying at its base a metallic comb 30 g^5 , the teeth whereof are arranged to mesh with teeth upon an endless card-clothing band m , which travels in the opening at the base of the hopper adjacent to the endless conveyer f . The block g also carries an upwardly and inwardly projecting arm n , which 35 as the block g slides inwardly is adapted to force the flocculent material in the hopper proper downward and inward toward the conveyer f . The comb g^5 is hinged to the frame g^4 in such a manner that when the block g and frame g^4 move outwardly from the hopper proper the comb g^5 slides backward over the band m , as illustrated in dotted lines in 40 Fig. 7. When, however, the block g and frame g^4 move inwardly in the hopper proper, the comb g^5 remains in a vertical position, as 45 illustrated in full lines in Fig. 7, and the teeth of the comb g^5 tear or separate the flocculent material and spread it evenly upon the band m . The vertical adjustment of the frame g^4 and its comb g^5 in the block g is accomplished, 50 preferably, by a spindle g^7 , screw-threaded at its lower end to engage the frame g^4 and turning loosely upon the base of the arm n . A 55 handle g^8 serves as a means to turn the spindle g^7 . The reciprocation of the block g in the hopper is preferably secured by a link o , connecting the block g with a crank-disk o' , driven by the machine. The card-clothing 60 band m carries the flocculent material from

the hopper to a set of card-clothing rolls m' and m^2 , which in turn transfer it to the initial roll d^2 of the carding mechanism.

The operation of the machine is as follows: A quantity of flocculent material—flaky asbestos, for example—is deposited in the hopper proper. The endless conveyer f serves to feed the material downward to the endless card-clothing band m , which in turn carries the material forward until the comb g^5 can 70 act upon it to distribute it over the band m in proper condition. The backward movement of the block g , frame g^4 , arm n , and comb g^5 in the hopper serves to tear the material on the band m and also serves to force the material backwardly and downwardly in the hopper to the conveyer f . A perfect agitation and distribution of the material in the hopper is thus obtained. The band m then conveys the material to the rolls m' and m^2 75 to the roll d^2 and to the series of peripheral rolls d^3 , d^4 , and d^5 , coacting with the carding-drum d' , which cards the material still further. The material is delivered from the drum d' to the under plane of the band b , and this band b conveys it to the rotating and traveling wire B after said wire B has been coated with an adhesive substance, whereby through the rotation and travel of the coated wire the material will be spirally wound 80 thereon.

Having thus described the nature and object of my invention, what I claim as new, and desire to secure by Letters Patent, is—

1. In a machine of the character described, 100 a hopper for the reception of flocculent material, a conveying and distributing means for the flocculent material, and an endless card-clothing band arranged to convey the material to a wire adapted to spirally apply the 105 material upon the same.

2. In a machine of the character described, 110 a hopper for the reception of flocculent material and provided with side walls, wings projecting from said walls and forming the discharge for said hopper, a block and frame arranged to reciprocate between said wings, a comb depending from said frame, and an endless card-clothing band traversing said 115 hopper and having its teeth coacting with the teeth of said comb.

3. In a machine of the character described, 120 a hopper for the reception of material having downwardly-inclined side walls separated at their base by a passage-way, an endless conveyer traveling downwardly and obliquely in said passage-way, wings projecting from the side walls to form an outlet from the hopper, an endless band of card-clothing traversing 125 the hopper between said wings, a block arranged to reciprocate between said wings, a comb depending from said block and having its teeth coacting with the teeth of said band, and an upwardly and inwardly extending 130 arm projecting from the block into said hop-

per, said arm adapted to force the material in the hopper toward the conveyer and the latter to discharge the material to said card-clothing band.

5 4. In a machine of the character described, in combination with means for feeding and rotating the wire, of an endless card-clothing band arranged at an angle to the plane in which the wire travels and means for supplying said band with flocculent material.

10 5. In a machine of the character described, in combination with means for feeding and rotating the wire, of an endless card-clothing band having its under face arranged adjacent to the wire and at an angle to the plane in which said wire travels, and means for supplying the under face of said band with flocculent material.

15 6. In a machine of the character described, a hopper for the reception of material, a card-clothing band arranged in said hopper, a block having a comb adapted to engage said card-clothing band and material, means to reciprocate said block and comb over said band, an arm adapted to engage said mate-

rial and an endless conveyer, said arm adapted to push the said material toward said conveyer and the latter to move the said material toward said card-clothing band.

20 7. In a machine of the character described, a hopper for the reception of material, a card-clothing band, a block having a comb adapted to engage said card-clothing band and material, means to reciprocate said block and comb over said band, an arm projecting from said block and adapted to engage said material and an endless conveyer, said arm adapted to push said material toward said conveyer and the latter to move said material toward said card-clothing band and said 35 comb arranged to control the amount of material fed forward by said card-clothing band.

25 In testimony whereof I have hereunto set my signature in the presence of two subscribing witnesses.

JOHN ALLEN HEANY.
